UNITED STATES PATENT OFFICE.

ERNEST W. LILJEGRAN, OF MEDFORD, OREGON.

TREE-PROTECTOR.

1,072,340.

Specification of Letters Patent.

Patented Sept. 2, 1913.

Application filed August 28, 1912. Serial No. 717,563.

To all whom it may concern:

Be it known that I, ERNEST W. LILJEGRAN, a citizen of the United States, residing at Medford, in the county of Jackson 5 and State of Oregon, have invented new and useful Improvements in Tree-Protectors, of which the following is a specification.

This invention relates to tree protectors, the object in view being to simplify and improve 10 the construction disclosed in my co-pending application, filed May 25th, 1912, Serial No. 699,815.

One object of the present invention is to provide means whereby the booms and the 15 cover carried thereby may be more readily and accurately folded upward against the mast, so as to admit of the protector being collapsed and placed between the branches or limbs of the tree, in connection with 20 which it is used.

A further object of the invention is to provide means whereby the mast may be folded to more effectually house the body of the protector among the branches or limbs 25 of the tree.

One of the principal objects of this invention is to provide means for depressing the booms with certainty, upon releasing the operating cords, so as to cause said booms to 30 move from their folded to their spread out or operative positions, thereby insuring the proper spreading of the cover or canopy of the protector.

With the above and other objects in view, 35 the invention consists in the construction, combination and arrangement of parts, as will be hereinafter more fully described, illustrated in the accompanying drawings, and pointed out in the claims hereunto appended.

In the drawings: Figure 1 is a side elevation of a tree protector, embodying the present invention. Fig. 2 is a plan view thereof. Fig. 3 is a side elevation, showing 45 the curtain raised. Fig. 4 is a similar view, showing the protector fully collapsed with the booms swung upward against the mast.

Fig. 5 is an enlarged diametrical section through the upper portion of the protector. 50 Fig. 6 is a plan view of the center portion

of the protector, omitting the cover. Fig. 7 is a detail view, showing the connection between the relatively folding portions of the mast. Fig. 8 is a detail perspective view of one of the spring holding clips, showing a portion of one of the springs. Fig. 9 is an enlarged detail section of the combined coupling and clamp for the frog. Fig. 10 is a similar view of the top collar, mast, head and clamping nut. 60

The tree protector contemplated in this invention comprises essentially a mast which, in the preferred embodiment of the invention, is shown as comprising an upper section 1, an intermediate section 2, and a lower section 3, the sections 2 and 3 being connected by a joint, as shown, the two sections 2 and 3 being made out of metal tubing and having the adjacent ends thereof mashed down flat, as shown at 4, and connected by means of a bolt 5 and a thumb nut 6. Between the overlapping ends 4 of the mast sections, a friction plate 7 is interposed, said plate being roughened, serrated, or toothed on its opposite faces, so that when 75 the flattened ends of the mast sections are clamped firmly together with the aid of the nut 6, the friction plate 7 will prevent any accidental collapse of the upper section relative to the lower section of the mast. 80

The adjacent ends of the sections 1 and 2 are threaded, as shown at 7', and are connected together by a coupling 8 in the form of an internally threaded sleeve, as best illustrated in Fig. 9. Supported upon the coupling 8 is a disk-shaped frog 9 which is held in place on the coupling by means of a clamping nut 10. The frog 9 is provided on its upper side with a circular series of slotted lugs 11, to which the inner ends of a series of radiating booms 12 are pivotally connected, at 13, thereby adapting said booms to swing from their normally horizontal spreading position upwardly to a substantially vertical position, as shown in Fig. 4. 95

In connection with each pair of booms 12, I employ a spring, the central portion of which is bent in U-shape, as shown at 14, and clamped against the upper face of the 100

frog 9 by means of a sheet metal clip 15. This clip 15 is punched to form a tubular internally threaded boss 16 adapted to receive a clamping screw 17 passing upward through a corresponding hole in the frog 9, while the opposite edges of the clip 15 are bent down to form confining flanges 17, within which the U-shaped portion 14 of the spring is held, the rear or inner edge of the clip being also bent downward to form a flange 18 which rests against the frog.

The terminal portions of the spring are bent to form the oppositely arranged coils 19, and they terminate in outwardly diverging spring arms 20, the extremities of which are bent into the form of eyes 21, through which the booms 12 pass, thereby providing for a relative sliding movement between the booms 12 and the eyes 21 of the spring arms, in order to permit the booms 12 to be swung upwardly and downwardly.

22 designates a cover of fabric extending around the mast and outwardly over the extremities of the booms 12, and then down to any suitable distance to form a pendant curtain 23. Secured to the inner face of the curtain 23 are rings or guide loops 24, through which pass operating cords 25. These cords have weights 26 attached to their lower extremities, and the cords pass upward through eyes 27, near the extremities of the booms 12, and also through openings 28 in the cover, thence upward over the top of the cover 22 and inward through guide openings 29 in a cap piece or mast head 30 threaded upon the upper end of the upper section 1 of the mast.

Surrounding the mast, just below the head or cap 30, is a collar 31 held in place by a nut 32 threaded on the mast below the collar. From said collar stays 33 extend outward to the end portions of the booms 12, to which they are connected, as shown at 34, the stays serving to limit the downward movement of the booms 12 and sustain the same in a substantially horizontal position.

All of the cords passing in through the guide openings 29 in the mast head extend downward through the tubular mast and outward through a hole 35 in the bottom end thereof, as shown in Fig. 5, so that by pulling on all of the cords, the entire set of booms may be simultaneously swung upward or allowed to be drawn downward by the action of the boom depressing springs hereinabove described.

From the foregoing description, it will be seen that the device is adapted to be used in connection with fruit and other trees, the mast extending upward through the limbs of the tree, and the cover or canopy being spread over the top of the tree, while the curtain is allowed to descend any suitable distance, so as to encompass and inclose the branches. The springs serve to

hold the booms at the lower limit of their pivotal movement, thereby retaining the protector in a spread out condition, and said springs serve to throw the booms downward, after the device has been completely folded to the position shown in Fig. 4.

When it is desired to expose the tree, the device is collapsed, as shown in Fig. 4, and by then loosening the thumb nut 6, the lower section of the mast may be drawn to one side, so as to permit the folded cover and booms to be slid downwardly among the branches of the tree, where the device will be protected against high winds. The manner in which the protector is adapted to be folded also facilitates the thrusting of the same upward through the central portion of the tree, preparatory to spreading the same out over the top of the tree.

What is claimed is:

1. A tree protector, comprising a tubular mast, booms pivotally connected with the mast, a cover of fabric supported by the booms and mast, boom depressing springs, and operating cords for swinging the booms and cover upward toward the mast.

2. A tree protector, comprising a tubular mast, booms pivotally connected with the mast, a cover of fabric supported by the booms and mast, boom depressing springs having arms in sliding engagement with the booms, and operating cords for simultaneously swinging the booms upward toward the mast.

3. A tree protector, comprising a tubular mast, booms pivotally connected with the mast, a cover of fabric supported by the booms and mast, boom depressing spring arms having terminal eyes through which the booms pass, and operating cords for simultaneously swinging the booms upward toward the mast.

4. A tree protector, comprising a tubular mast, booms pivotally connected with the mast, a cover of fabric supported by the booms and mast, a frog on the mast, boom depressing springs attached to said frog, and operating cords for simultaneously swinging the booms upward toward the mast.

5. A tree protector, comprising a tubular mast, booms pivotally connected with the mast, a cover of fabric supported by the booms and mast, a frog on the mast, a sleeve threaded on the mast at one side of the frog, a clamping nut at the opposite side of the frog, boom depressing springs attached to the frog, and operating cords for simultaneously swinging the booms upward toward the mast.

6. A tree protector, comprising a tubular mast, booms pivotally connected with the mast, a cover of fabric supported by the booms and mast, a frog on the mast having the booms pivotally attached thereto, boom

depressing springs also attached to said frog, and operating cords for simultaneously swinging the booms upward toward the mast.

5 7. A tree protector, comprising a tubular mast, booms pivotally connected with the mast, a cover of fabric supported by the booms and mast, a frog on the mast, boom depressing springs each embodying two

spring arms engaging adjacent booms, and 10 clips fastening said springs to the frog.

In testimony whereof I affix my signature in presence of two witnesses.

ERNEST W. LILJEGRAN.
